ABSTRACT OF THE DISCLOSURE

This invention is a portable utilities cabinet, and consists of light weight casing in which is mounted a battery powered fan, an exterior flashlight powered from the same battery, and a catalytic heater which may be turned on or off from the outside of the casing so that, when off, the fan may be used to create a cooling draft, and when on, a warming draft, through appropriately located vents on one side thereof. Also, a pocket is provided on one exterior wall, which may be used to carry a small transistor radio or other suitable object as desired. The casing may be of any suitable material such as high impact plastic or metal, and when of metal, the casing may provide a ground for the battery to the fan motor as well as to the exterior flashlight.

OBJECTS OF THE INVENTION

It is an object of this invention to provide a portable lightweight utilities cabinet, easily carried by a carrying handle or shoulder strap, and which provides the carrier with a source of heat or cooling, and also a flashlight, and has a pocket for carrying a transistor radio or other small convenience.

Still a further object of this invention is to provide a portable utilities cabinet, which is as convenient to carry as a handbag or lunch pail, and which will provide, at will, cooling, or heating, as well as a flashlight and a pocket carried transistor radio.

Yet a further object of this invention is to provide a portable utilities cabinet having a fuel inlet extending through one wall thereof to a non-spill fuel tank therewithin for providing the heat, with a heat control means accessible from outside the cabinet so that a warm draft of air may be provided as desired, by means of a battery operated fan therewith and when the heat is turned off, may be used for providing a cooling draft of air from the same fan.

DESCRIPTION OF FIGURES

With the above and related objects in view, this invention consists in the details of construction and combination of parts, as will be more fully understood from the following description, when read in conjunction with the accompanying drawing, in which:

FIG. 1 is a perspective view of the portable utilities cabinet of this invention.

FIG. 2 is a sectional view on line 2—2 of FIG. 1.

FIG. 3 is a sectional view on line 3—3 of FIG. 1, the valve being in a closed position.

FIG. 4 is a sectional view on line 4—4 of FIG. 3.

FIG. 5 is a sectional view also on line 4—4 of FIG. 3, but with the valve in open position.

DESCRIPTION OF THE INVENTION

There is shown at 10 the portable utilities cabinet of this invention, the utilities provided by this invention consisting of heating, cooling and light, and also radio when the pocket has a transistor radio carried therein. The cabinet 10 includes a completely enclosed casing 12, of high impact plastic, metal, or other suitable material. As shown any suitable conventional means may be used

2

for making it possible to open the casing 12 when necessary, the means illustrated consisting of overlapping edges 14 of upper and lower portions 16 and 18 of the casing detachably secured together by screws 20. A handle 22 on the top of upper portion 16 is provided, and a shoulder strap, of conventional construction, may be used if desired, the overall size of the casing 12 being that of a small lunchbox or handbag. Secured on an inner wall of the upper portion 16 is a small electric motor 24 powered by a battery 26 also secured on the same wall. A circuit 28 from battery 24 through the motor 24 is connected to exterior control switch 30 and then back to the battery to complete the circuit. When the casing 12 is of metal, the return circuit may be grounded therethrough, as shown. A fan 32 mounted on the shaft of the motor 24 is thus controlled by the switch 30. A second circuit 34 from the same battery 26 is connected through a second exterior control switch 36 to a flashlight at 38 and back to the battery, through ground as shown, or through a return wire if necessary.

An outlet vent grill 40 provided in the opposite wall of the casing 12 permits a draft of air to be directly externally of the casing 12, a suitable inlet air vent 42 being provided below the fan 32. When no heat is desired, the fan 32 provides a cooling draft through the outlet vent 40, when switch 30 is moved to "on" position. When switch 36 is moved to "on" position, the flashlight 38 lights up.

The heating utility is provided as follows: An elongate cylindrical fuel tank, 44, filled with an absorbent material 46, making the tank have non-spill properties, is mounted on two legs 48 secured by screws 50 through the lower portion bottom wall. A cap 52 threaded on the end provides access to the interior of the tank, and a capped fill pipe 53 extends through a side wall of the casing to permit easy refuelling when needed, without disassembling the casing 12.

Secured adjacent each end of the tank 44 is an elongate cylindrical housing 54 having an elongated bottom opening 56 coinciding with a similar elongate opening in the top of the fuel tank 44, so that fuel vapor may rise therethrough. An elongate cylindrical valve 58 is provided with an elongate valve passage 60 therethrough, the valve passage 60 permitting fuel vapor to pass up therethrough when the passage 60 coincides with the fuel and housing opening 56. Another elongate opening 62 on top of valve housing permits the fuel vapor to rise therethrough, when the valve 58 is in open position as shown in FIGURE 5, and reach an elongate catalytic wick 64 supported in a perforated chamber 66 mounted on the top of the valve housing 54, chamber 66 having an elongate opening coinciding with housing to opening 62. The catalytic wick is of the type commonly referred to as catalytic combustor type heating devices, such as shown in U.S. Pats 3,199,505 and 3,099,258 to provide heat without flames, and the catalyst may contain platinum or platinum chloride maintained at a suitable temperature by a flame wick 68 located in a flue 70, the flue 70 continuing to the perforated catalytic chamber 66 under a hood 72 extending over the catalytic chamber 66.

A plurality of radiator vanes 74 extend from the hood 72 in the path of the air from the fan 32, so that when heat is produced by the catalytic wick 64, a warm draft will come out of the outlet grill 40. The flame wick 68 may be ignited by a flint 76, of the type usually found on cigarette lighters, and is sparked by a striker wheel 78 located in the flue 70 on the end of one shaft 80 of a pair of shafts 80 and 82 on which the rotatable valve 58 is journaled in its housing 54, the end of the other shaft 82 extending exteriorly of the casing 12 where it is provided with a knurled knob 84 for opening and closing the valve 58 as well as for igniting the flame wick 68. A hinged door 86 in the casing 12 adjacent the flame wick

68 may be provided for extinguishing the flame on the flame wick 68 when desired. A pocket 88 is attached to an exterior wall of casing 12 suitable for insertion of a transistor radio or other suitable convenience.

OPERATION OF THE INVENTION

In operation, the fuel valve 58 is normally in closed position, as shown in FIGS. 3 and 4 when the cabinet is not being used for either cooling or heating. If cooling is desired, the fan switch 30 is actuated, to cause the fan 32 to create a cooling draft out through the air outlet vent 40. If warming draft is desired, then the knurled knob 82 is also rotated to cause the striker wheel to be operated against flint 76 and create a spark to ignite flame wick 68, and the hood 82 is stopped in the "open" position. The flame wick 68 will then heat the catalytic wick 64 to an active catalytic temperature to cause the fuel vapor to unite with oxygen of the air and heat the air being blown by the fan 32 over the vanes 74 and out the air outlet vent. To discontinue the heat, the knurled knob is turned to "closed" position, cutting off the fuel vapor from the catalytic wick 64, and the door 86 is opened to enable the flame on flame wick 68 to be extinguished. The transistor radio in pocket 88, if present, may be used when desired, either in position in the pocket 88, or removed therefrom and carried in the hand or a clothing pocket.

ABSTRACT OF THE DRAWING

In the drawings, like members refer to like parts, and for purposes of explication, marshalled below are the numbered parts of the improved portable utilities cabinet:

- 10 portable utilities cabinet
- 12 casing
- 14 overlapping edges
- 16 upper portion of 12
- 18 lower portion of 12
- 20 screws through 14
- 22 carrying handle
- 24 electric motor
- 26 battery
- 28 fan circuit
- 30 exterior control switch for fan motor
- 32 fan
- 34 flashlight circuit
- 36 exterior flashlight switch
- 38 flashlight
- 40 air outlet vent
- 42 air inlet vent
- 44 fuel tank
- 46 non-spill absorbent material in tank 44
- 48 legs of tank 46
- 50 screws to legs 48
- 52 tank cap
- 53 capped fill pipe
- 54 cylindrical valve housing
- 56 elongate opening in top of tank 44 and bottom of valve housing 54
- 58 rotatable valve
- 60 passage through 58
- 62 elongate valve opening in top of housing 54
- 64 catalytic wick
- 66 perforated chamber about catalytic wick
- 68 flame wick
- 70 flue
- 72 hood
- 74 radiator vanes
- 76 flint

- 78 striker wheel
- 80 valve shaft with wheel 78
- 82 valve shaft with knurled handle knob 82
- 84 knurled handle knob on shaft 82
- 86 hinged door in casing adjacent flame wick 68
- 88 pocket for holding transistor radio, etc.

Although this invention has been described in considerable detail, such description is intended as being illustrative rather than limiting, since the invention may be 10 variously embodied, and the scope of the invention is to be determined as claimed.

Having thus set forth and disclosed the nature of this invention, what is claimed is:

- 1. A portable utilities cabinet 10 comprising an enclosed casing 12, a fan 32 mounted for operation on one side wall of said casing 12, an air vent 40 extending through the opposite side wall, and means for powering said fan for operation, a non-spill fuel tank 46 secured along the bottom of said casing 12, said tank 44 having a fuel vapor releasing opening 56 along its top side, a catalytic wick 64 mounted over said vapor opening 56, and a flame wick 68 from said fuel tank 44 to a flue 70 leading to said catalytic wick 64 for activating said catalytic wick, and a hood 72 extending about said catalytic wick 64, and a plurality of radiator vanes 74 extending from said hood 72.
- 2. The cabinet of claim 1, said fan powering means comprising an electric motor 24.
- 3. The cabinet of claim 2, and a battery electricity supply 26 in circuit 28 to said motor 24.
- 4. The cabinet of claim 1, and a perforated extension 66 of said flue 70 enclosing said catalytic wick 64 within said hood 72.
- 5. The cabinet of claim 1, said cabinet having air inlet means 42.
- 6. A portable utilities cabinet 10 comprising an enclosed casing 12, a fan 32 mounted for operation on one side wall of said casing 12, an air vent 40 extending through the opposite side wall, and means for powering said fan for operation, a non-spill fuel tank 46 secured along the bottom of said casing 12, said tank 44 having a fuel vapor releasing opening 56 along its top side, a catalytic wick 64 mounted over said vapor opening 56, and a flame wick 68 from said fuel tank 44 to a flue 70 leading to said catalytic wick 64 for activating said catalytic wick, and a rotatable valve 58 for controllably opening and closing said vapor releasing opening 56, a shaft 80, 82 on each end of said rotatable valve 58 on 40 which it is rotatably supported, one end of one 82 of said shafts extending exteriorly of a wall of said casing 12 and handle means 84 on said exterior shaft end 82 for rotating said valve 58, a striker wheel 78 on the end of said other shaft 80, said striker wheel 78 being located 45 in said flue 70, and a flint 76 in contact with said striker wheel 78 for igniting said flame wick 68 when said handle means 84 is rotated.
